UNITED STATES PATENT OFFICE.

FRANCIS M. MORGAN, OF SAN FRANCISCO, CALIFORNIA.

FACIAL-CONTOUR RESTORER.

1,321,137.

Specification of Letters Patent.

Patented Nov. 11, 1919.

Application filed July 7, 1919. Serial No. 309,112.

To all whom it may concern:

Be it known that I, FRANCIS M. MORGAN, a citizen of the United States, residing in the city and county of San Francisco and 5 State of California, have invented certain new and useful Improvements in Facial-Contour Restorers, of which the following is a specification.

The present invention relates to an application adapted for use for restoring the facial contour, the particular object of the appliance being to tighten or stretch the flesh beneath the chin whereby double chins, which are common with elderly people, are 15 eliminated.

The device is adapted for daily use and is capable of adjustment to fit the head of any person, the same consisting preferably of a member which is passed over the head with 20 its terminal ends lying adjacent the cheeks immediately in front of the ears and beneath the head dress, said terminal portions being adhesively secured or attached to the cheeks, whereby when the slack in the support is taken up, the flesh on opposite sides 25 of the face will be slightly raised.

With the above mentioned and other objects in view, the invention consists in the novel construction and combination of parts 30 hereinafter described, illustrated in the accompanying drawings and pointed out in the claims hereto appended; it being understood that various changes in the form, proportion, size and minor details of construction 35 within the scope of the claims may be resorted to without departing from the spirit or sacrificing any of the advantages of the invention.

To more fully comprehend the invention, 40 reference is directed to the accompanying drawings, wherein—

Figure 1 is a view of the appliance in use.

Fig. 2 is a view in plan of the appliance with the parts thereof assembled.

Fig. 3 is a view in side elevation.

Fig. 4 is a view in detail of the adjusting means.

Referring more particularly to the drawings, wherein like characters of reference 50 designate corresponding parts, 1 indicates a support of any suitable material, either fabric or thin metal, and if constructed of metal, the same is bent to semi-circular form in plan and is adapted for positioning over 55 the head with the terminal ends thereof ly-

ing at points preferably adjacent the temples. The support 1 is adapted for wearing either during the day, at which time it is concealed beneath the head dress, or at night, over the hair.

To the ends of the support, illustrated in Fig. 1, are secured, in any suitable manner, the adjustable clamps 2 of any well known construction, preferably that type commonly employed in retaining tie pins within ties, the same consisting preferably of a tubular outer shell 3 and a tubular inner shell 4, the inner shell carrying the clamping balls 5, which ride on the beveled surface 6 of the outer shell 3, said balls being normally maintained in frictional contact with the beveled surface by the spring 7 co-operating with the shells 3 and 4.

Suitable tabs or flaps 8 of any suitable configuration and any of suitable material 75 are employed for providing a connection between the flesh and the support 1 and said tabs or flaps 8 are formed preferably with an adhesive face which is pressed into contact with the flesh, as in Fig. 1 of the drawings.

The upper ends of the tabs 8 carry suitable eyes or other fastening means 9 with which are engaged the hooked or bent lower ends 10 of the adjusting rods or members 11, 85 one positioned at each side of the face with its upper end extending through the adjustable clamp 2.

In use, the support 1 is positioned over the head, preferably as in Fig. 1, and the hair is brought back to overlie and conceal the same. The tabs 8 are adhesively applied one to each cheek preferably below the temple and immediately in front of each ear and the hooked portions 10 of the adjusting rods 95 11 are passed through the loops or eyes 9. When in this position, the flesh of the cheeks is raised, which permits of the passing upwardly of the members 11 through the adjusting clamps 2 until the skin is sufficiently 100 stretched underneath the chin to eliminate the flabby portion which forms the commonly termed "double chin". The construction of the clamps 2 being such as to prevent the free downward movement of the members 11 relatively thereto until such time as the inner tubular shell 4 of the respective clamps is raised, releasing the clamping balls 5 from contact with the beveled surface 6.

Having thus described my invention, what I claim as new and desire to protect by Letters Patent is:—

1. An apparatus for the described purpose comprising a support for passing transversely over the head and terminating at its ends adjacent the cheeks, an adjusting clamp associated with the opposite ends of said support, an adjusting rod associated with each clamp, and a member associated with each rod for detachably securing to the cheeks.
2. An apparatus for the described purpose comprising a curved metallic member providing a support and adapted for positioning transversely of the head with its opposite ends terminating one adjacent each

cheek, an adjusting clamp associated with each end of said support, an adjusting rod associated with each clamp and each provided with a hook at its lower end, and a member associated with each rod and each having an adhesive surface for application to the cheek, and a loop associated with each member and through which said hooks extend.

In testimony whereof I have signed my name to this specification in the presence of two subscribing witnesses.

FRANCIS M. MORGAN.
